UNITED STATES PATENT OFFICE.

GEORGE L. TURNER, OF TAUNTON, MASSACHUSETTS.

DESIGN FOR A SPOON, FORK, OR SIMILAR ARTICLE.

48,336.

Specification for Design.

Patented Dec. 21, 1915.

Application filed October 11, 1915. Serial No. 55,341. Term of patent 14 years.

To all whom it may concern:

Be it known that I, GEORGE L. TURNER, a citizen of the United States, residing at Taunton, in the county of Bristol and Commonwealth of Massachusetts, have invented a new, original, and ornamental Design for a Spoon, Fork, or Similar Article, of which the following is a specification, reference being had to the accompanying drawing, forming a part thereof.

The figure is a plan view of a spoon or fork showing my new design.

I claim—

The ornamental design for a spoon, fork or similar article as shown.

GEORGE L. TURNER.

Witnesses:

GEORGE F. PARKER,
AUGUST C. MILLER.
